UNITED STATES PATENT OFFICE.

GEORGE WASHINGTON MONTGOMERY, OF SPRINGBORO, PENNSYLVANIA, ASSIGNOR OF
ONE-HALF TO MARK D. BOWMAN, OF SPRINGBORO, PENNSYLVANIA.

HAY-LOADER.

1,112,080.

Specification of Letters Patent.

Patented Sept. 29, 1914.

Application filed July 19, 1912. Serial No. 710,510.

To all whom it may concern:

Be it known that I, GEORGE W. MONTGOMERY, a citizen of the United States, residing at Springboro, in the county of Crawford and State of Pennsylvania, have invented a new and useful Hay-Loader, of which the following is a specification.

This invention relates to hay loaders, its primary object being to provide, in a single machine, a rake, a hay elevating apparatus, and a wagon.

Another object is to provide mechanism of this character which is light and durable in construction and which receives its power from the front wheels of the machine.

Another object is to provide a combined rake and loader or elevator which can be readily moved into or out of active position, the shifting of the parts out of active position resulting in the disconnection of the loading mechanism from the drive wheels.

A further object is to provide a rake and loader which will remain constantly in the same relation to the surface of the ground, thus rendering the machine especially desirable for use over uneven ground.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

40 In said drawings:—Figure 1 is a side elevation of the machine. Fig. 2 is a front elevation thereof. Fig. 3 is a horizontal section through the stacker and showing its operating mechanism in plan. Fig. 4 is a detail view of a caster wheel used under the elevator.

45 Referring to the figures by characters of reference 1 designates the body of a wagon, the same supporting a rack 2 and being mounted, at its rear end, upon a wheel supported axle 3 of the usual or any preferred type. In lieu of that portion of the running gear ordinarily provided at the front end of a wagon, running gear of special form is 50 employed. This includes a front or steering

axle 4 having supporting wheels 5. A frame 6 is carried by the revoluble front axle and the draft tongue 7 is connected to the front portion of this frame, preferably at the center thereof.

55 Side arms 8 are pivotally mounted on and extend forwardly from the end portions of the axle 4 and their front ends engage the end portions of a transverse shaft 9 journaled in the sides of an upwardly extending inclined frame 10. The sides of this frame are provided with longitudinal slots 11 for the reception of pins 12 which extend inwardly from the upper end portions of standards 13. These standards are fixedly 60 connected to the sides of the frame 6.

65 A transverse shaft 14 is journaled in the upper portion of the frame 10 and has sprockets 15 which are engaged by endless chains 16, these chains extending downwardly and under sprocket 17 secured to the shaft 9. Transverse slats 18 connect the chains and extending outwardly from certain of the links of the chains are teeth 19. Casters 20 are connected to the lower ends 70 of the sides of frame 10 and are designed to normally bear upon the ground. Journaled in brackets 21 mounted on the front portion of frame 6 is a shaft 22 having rearwardly extending arms 23 adjacent its ends and 75 which are connected, as by means of links 24, to the sides of the frame 10. A lever 25 extends upwardly from the shaft 22 and is provided with a spring pressed pawl 26 adapted to engage a toothed segment 27 80 whereby the shaft 22 is held against rotation.

85 In the accompanying drawings the preferred form of the invention has been shown. 90 Each of the wheels 5 has a clutch member 28 revoluble therewith and feathered on the axle 4 and adjacent each of these clutch members is another clutch member 29 movably engaged by one arm of a bell crank lever 30. Rods 31 connect the other arms of the bell crank levers to arms 32 extending radially from the end portions of the shaft 22. The 95 bell crank levers 30 are fulcrumed on brackets 33 secured to the frame 6.

100 The parts are so positioned and proportioned that, when the casters 20 are in contact with the ground and the frame 10 is thus in its lower position, the clutch members 29 are in engagement with clutch members 28 and the wheels 5 thus coupled to the axle 4. Secured to the frame 6 and extending transversely thereof back of the 105 110

shaft 9 is a series of spring rake teeth 34. An inclined board 35 extends upwardly from the upper ends of the teeth 34 and overhangs the rack 2, this board being provided with side flanges 36 which are bolted or otherwise secured to the standards 13, the lower end of the board being secured in any desired manner to the frame 6.

When the machine herein described is to 10 be moved without gathering hay, the lever 25 is swung downwardly and forwardly so as to cause the arms 23 to pull upwardly on links 24. The frame 10 will therefore be elevated, the slotted portions of the frame 15 sliding along the pins 12. At the same time the casters 20 will be lifted out of contact with the ground and the teeth 34 will also be raised. During this rotation of shaft 22 the arms 32 thereon will push on the rods 20 31 and cause the bell crank levers 30 to shift the clutch members 29 out of engagement 25 with the clutch members 28. Wheels 5 will thus be uncoupled from axle 4 and the axle will not be rotated as the machine travels forward.

When it is desired to use the apparatus 30 for gathering and elevating hay, the lever 25 is shifted back to the position shown in Fig. 1, whereupon the frame 10 moves downwardly so as to bring the casters 20 and the teeth 34 into contact with the ground and the clutch members 29 move into engagement with the clutch members 28, thus coupling the wheels 5 to the axle 4.

Obviously, therefore, as the machine 35 moves forward, motion will be transmitted from the axle 4 through sprockets 37, which are secured to the axle, to chains 38, and these chains will, in turn, drive sprockets 39 40 which are secured to the shaft 9. Thus the endless conveyer will be set in motion and the teeth 19 outstanding therefrom will engage the hay gathered by the teeth 34 and drag it upwardly along the board 35 so as 45 ultimately to discharge it onto the rack 2. Thus it will be seen that, as the machine moves forward, the hay in the path thereof will be gathered by the teeth 34, will be engaged and elevated by the teeth 19 on the 50 elevator, and will be finally discharged onto

the rack. As the frame 10 is slidably mounted between the standards 13 the casters 20 are free to travel along an uneven surface and will thus maintain the teeth 34 at all times in proper relation to the ground. The pawl 26 is only used for engaging the rack 27 when the elevator is raised out of operative position. At other times the lever 25 is free to swing and not hinder the up and down movement of the 60 elevator frame 10 while traveling over an uneven surface.

What is claimed is:—

1. The combination with a wheel supported structure of an upwardly extending elevator, means for connecting the same to said structure, means for supporting the elevator normally at a predetermined distance from the ground, a rake for directing material into engagement with the 65 elevator, means for driving the elevator from a supporting wheel, a lever, and separate means operated by said lever for simultaneously shifting the elevator upwardly 70 away from the ground and uncoupling said driving mechanism from the axle.

2. The combination with a wheel supported structure including an axle adapted to be rotated by said wheels, of a rack connected to and movable with the structure, an elevator overhanging the rack and mounted on 80 said structure, a connection between the elevator and structure, means for sliding the elevator upwardly and downwardly relative to the structure, rake teeth for gathering 85 material and directing it into engagement with the elevator, a board extending under the elevator and overhanging the rack for supporting material engaged by the lower flight of the elevator, and means for transmitting motion from the said axle to the elevator irrespective of the sliding movement 90 of the elevator.

In testimony that I claim the foregoing as my own, I have hereto affixed my signature in the presence of two witnesses.
